UNITED STATES PATENT OFFICE

LAWRENCE S. WILLIAMS, OF TOLEDO, OHIO, ASSIGNOR TO TOLEDO SCALE MANUFACTURING COMPANY, OF TOLEDO, OHIO, A CORPORATION OF NEW JERSEY

DESIGN FOR A FONT OF TYPE

Application filed November 2, 1931. Serial No. 41,589. Term of patent 14 years.

To all whom it may concern:

Be it known that I, LAWRENCE S. WILLIAMS, a citizen of the United States, residing at Toledo, in the county of Lucas and State of Ohio, have invented a new, original, and ornamental Design for a Font of Type, of which the following is a specification, reference being had to the accompanying drawing, forming a part thereof.

The drawing illustrates a font of type comprising the numerals 0 to 9, showing my new design.

I claim:

The ornamental design for a font of type substantially as shown.

LAWRENCE S. WILLIAMS.
